MUSIC BOX

Eric Wedemeyer, Floral Park, N. Y., assignor to
 Hamilton Art Metal Corporation, New York,
 N. Y., a corporation of New York

Application December 30, 1944, Serial No. 570,519

9 Claims. (Cl. 84—95)

1

This invention relates to a musical box, more particularly to a musical box cigarette dispensing apparatus of the so-called "Tudor" type, and more especially to the mechanism for operating the cigarette holding two doors thereof.

An object of the invention is to provide, in a musical box, an improved mechanism operated by the motor driving the musical instrument and reliably and simultaneously opening and closing a pair of doors pertaining to said musical box.

An object of the invention resides in the provision of a mechanism of the type set forth above having one operating crank and two individual link connections individually connected and operated by said crank and individually connected with and operating the doors of the music box.

A further object of the invention is the provision of an improved pusher or plunger mechanism for starting the music and door operating mechanism whereby damage to the musical instrument and its driving motor as well as to the pusher mechanism is prevented.

Further and other objects of the present invention will be hereinafter set forth in the accompanying specification and claims and shown in the drawings which, by way of illustration, show what I now consider to be a preferred embodiment of my invention.

In the drawings:

Fig. 1 is a part sectional top view of the musical box and particularly of the door operating mechanism according to the invention.

Fig. 2 is a part sectional front view of the musical box and particularly of the door operating mechanism according to the invention.

Fig. 3 is a front view of the crank and link means according to the invention in upper dead center position.

Like parts are designated by like numerals in all figures of the drawings.

Numeral 1 in Fig. 1 designates the motor which is of the conventional music-box type and which revolves cylinder 2 having pins cooperating with the vibration comb 3. The motor is wound up by manipulating a key 4 disposed in a recess in the bottom of base plate 5. To prevent unwinding of the motor when the device is not used, a two arm lever 6, 6' is provided, swinging about fulcrum 7 and having a peg 8 at the end of arm 6' which peg, when the device is in inoperative condition, is inserted into a hole in gear wheel 9 and prevents rotation thereof.

For starting operation of the device, lever 6, 6' is turned counterclockwise whereby peg 8 is pulled out of its hole in wheel 9 and the latter

is free to rotate. The tip of the peg slides on wheel 9—this is the condition shown in Fig. 1—until the wheel has made a complete revolution, when the peg snaps again into its hole thereby preventing revolving of wheel 8 and stopping the mechanism. To assure this sliding of the peg on the wheel, a coil spring 10 is connected with the end of arm 6 of lever 6, 6' and with a stationary part of the device. For producing the small counterclockwise movement of lever 6, 6' needed for starting the mechanism, a plunger 11 is provided, guided and reciprocatingly movable in block 12. The outer end of plunger 11 carries a cap 13 disposed in a recess 14 of the outer wall of the music box proper. Cap 14 has a rim portion of larger diameter than plunger 11 and a coil spring 15 is inserted between said rim portion and the bottom of recess 14. This spring normally forces the plunger outward till the outer surface of cap 14 is flush with the outer surface 16 of the music box. A pin 17 which extends through plunger 11 prevents too far outward movement of the plunger by abutment on block 12. The inward movement of the plunger is limited by the fully compressed coil spring 15 filling up the space between the rim of cap 13 and the bottom of recess 14. Any damage to the lever 6, 6' and parts connected therewith by pushing the plunger too far inward is effectively prevented by the arrangement just described. Damage to the plunger and parts connected therewith which might occur if the outer end of the plunger projects beyond surface 16 is also effectively prevented. In Fig. 1 the plunger is shown in its innermost position to which it has been brought by depressing button cap 13 and in which it just has turned lever 6, 6' counterclockwise to pull peg 8 out of its hole and to permit rotation of cylinder 2 and parts connected thereto. By releasing button 13 the plunger snaps outward until pin 17 engages block 12, and the point of peg 8 slides on the surface of wheel 9 held thereto by the tension of spring 10.

The far end of cylinder 2 holds a crank 18 having a pin end 19. Two connecting links 20 and 21 are rotatably disposed on pin 19. Link 21 is bent at 22 to provide space between connecting links 20 and 21 for angle links 23 and 24 which are pivoted with their short arms to links 20 and 21 respectively, at 25 and 26 respectively. The long arm of angle link 23 is bent oppositely to the bend 22 of link 21 to provide space for angle link 24.

The long arm of link 23 is rigidly connected

with box portion 27 of door 28 and the long arm of link 24 with box portion 29 of door 30.

The doors are substantially vertical and swing about horizontal axes disposed near the upper closure of the lower compartment of the device which contains the musical instrument and the driving means therefor and a portion of the link means connecting the driving means and the swing doors for operation of the latter. The doors are adapted to close the upper chamber formed by the top 34 of the lower chamber, the side walls 35 and 36 and the top 37. Door 28 swings about fulcrum 32 and door 30 about fulcrum 33.

When peg 8 is released and the music plays, crank 18 turns clockwise. In the condition shown in Fig. 2 the crank has already moved 270° and the doors 28 and 30 are on their way back into closed position. When pin 19 has reached lower dead center position the doors are completely closed and in the position shown in dotted lines for the left door 30. When pin 19 is in upper dead center position which is shown in Fig. 3 the doors are fully open and in the position indicated in dotted lines for the right door 28. This is the position where a cigarette may be taken out of a pocket formed by the box portions 27 or 29 of the doors. In the position of the mechanism shown in Fig. 2 the hole for the peg 8 is in the position designed by numeral 31.

While it is believed that the above described embodiment of this invention is a preferred embodiment, it is to be understood that it is not desired to be limited to the exact details of method, design and construction shown and described, for obvious modifications will occur to a person skilled in the art.

I claim:

1. In a music-box comprising an outside wall portion, a musical instrument and driving means therefor within said box, locking means connected with said driving means and preventing operation thereof and comprising a lever, unlocking means comprising a plunger member having an end abuttingly cooperating with said lever, support means disposed in said box and movably supporting said plunger member, a cavity in said wall portion, the other end of said plunger member extending into said cavity, cap means connected with said other end of said plunger member and having an outer surface adapted to substantially close said cavity, resilient means disposed between said cap means and the bottom of said cavity and tending to force said plunger member out of said box, and stop means connected with said plunger member and adapted to abut against said support means and preventing further outward movement of said plunger member when the outer surface of said cap means is substantially flush with the outer surface of said wall portion adjacent said cavity.

2. In a music box comprising an outside wall portion, a musical instrument and driving means therefor within said box, locking and unlocking means connected with said driving means and comprising a plunger member extending through said wall portion, support means disposed in said box and movably supporting said plunger, resilient means connected with said plunger member and said box and tending to force said plunger member out of said box, and stop means connected with said plunger member and with said box and limiting the outward movement of said plunger member.

3. A music box system comprising, in combina-

tion, a box, a housing mounted on top of said box and having two opposed open sides, individual swing doors for individually closing said sides, each swing door comprising a container extending into said housing, a motor and a musical instrument driven thereby disposed in said box, and link means connecting said motor and said containers for simultaneously swinging in opposite directions and thereby opening and closing said doors by said motor.

4. A music box system as defined in claim 3, said motor having a crank and said link means comprising two individual sets of link members individually connecting said crank and said containers.

5. A music box system comprising, in combination, a box having a top portion, a housing mounted on said top portion and having two opposed open sides, a door for each open side swingably connected with said housing adjacent said box and swinging about an axis parallel to said top portion, each door comprising a container extending into said housing, a connecting means projecting from each container toward said box, and thereinto when the doors are closed, a motor and a musical instrument driven thereby disposed in said box and having a crank, and two individual link members individually swingably connected with said crank and with said connecting means.

6. A music box system comprising, in combination, a box having a top portion, a housing mounted on said top portion and having two opposed open sides, a door for each open side swingably connected with said housing adjacent said box and swinging about an axis parallel to said top portion, each door comprising a container extending into said housing, a connecting means connected with each container and having a lower portion projecting from the container and toward the lower portion of the connecting means of the other container and toward said box, and thereinto when the doors are closed, a motor and a musical instrument driven thereby disposed in said box and having a crank, and two individual link members individually swingably connected with said crank and with said lower portion of said connecting means.

7. A music box system as defined in claim 6, said connecting means being of L-shaped configuration with the long portion connected to the container and the short portion forming said lower portion.

8. A music box system comprising, in combination, a box, a housing mounted on top of said box and having two opposed open sides, individual swing doors for individually closing said sides, each swing door comprising a container extending into said housing, a motor and a musical instrument driven thereby disposed in said box and comprising a crank, individual link means individually connecting said crank and said containers and simultaneously swinging in opposite directions and thereby simultaneously opening and closing both doors upon one revolution of said crank.

9. A music box system as defined in claim 8, said motor comprising a shaft to which said crank is connected, a disc connected with said shaft and having an aperture, a lever slidably engaging said disc and swinging about a stationary pivot in said box and having a portion adapted to engage said aperture and prevent rotation of said disc, shaft, motor and crank, a spring connected with said lever and holding it against said disc,

and manipulatable means engaging said lever for moving it against the action of said spring and releasing it from said aperture for starting the motor.
